UNITED STATES PATENT OFFICE

2,570,966

LOOSE-LEAF POST BINDER

Henry H. Moore, Austin, Tex.

Application June 26, 1947, Serial No. 757,283

2 Claims. (Cl. 129—12)

1

This invention relates to looseleaf post binders. The invention is applicable to binders having the posts thereof disposed at any point longitudinally of the binder base or binder top, and provided with adjustable means whereby sheets having differently spaced perforations, and with different diameters of perforations, may be properly engaged by posts of different diameters which constitute a part of the binder.

In present-day post binders, the structure is not flexible, and a dealer is required to carry a large inventory in order to accommodate the numerous demands due to the different spacing of posts, as well as the different sizes of the posts and diameters of the perforations of the loose sheets going into post binders. Attempts to provide adjustable post supporting means at the ends and sides of the base member are unsatisfactory, because they weaken the metal base and are not adequate for the sturdy supporting of posts at any point longitudinally of the base member of the binder.

An object of the present invention is to overcome the above difficulty by making it possible to change the center-to-center spacing of the posts while also accommodating different sized posts in such center-to-center adjustments. A further object is to provide an extremely sturdy structure in which a binder base member of relatively light metal is effectively braced for the supporting of posts, while, at the same time, enabling the posts to be located in adjusted positions longitudinally of the base member. A further object is to provide a post binder structure in which the post supporting block is adjustably mounted in the binder base and adapted to be locked therein by rotating the post. Yet another object is to provide a binder base member of improved structure in which slots are provided for adjustment of the post supports, while, at the same time, providing reinforcements of metal for the hollow base coextensive with the slots. Other specific objects and advantages will appear as the specification proceeds.

The invention is illustrated in simple embodiments by the accompanying drawings, in which:

Figure 1 is a perspective view of a binder embodying my invention; Fig. 2, a broken top plan view of a portion of the binder structure; Fig. 3, a broken enlarged detailed sectional view, the sections being taken, as indicated, at line 3—3 of Fig. 2; Fig. 4, a broken enlarged detailed sectional view, the section being taken as indicated at line 4—4 of Fig. 2; Fig. 5, a broken top plan view of a modified form of the invention; Fig. 6, a broken sectional detailed view, the section being taken as indicated at line 6—6 of Fig. 5; Fig. 7, a broken sectional detailed view, the section being taken as indicated at line 7—7 of Fig. 5; Fig. 8, a broken top plan view of another modified form of binder embodying my invention; Fig. 9, a sectional detailed view, the section being

2

taken as indicated at line 9—9 of Fig. 8; and Fig. 10, a broken sectional view, the section being taken as indicated at line 10—10 of Fig. 8.

In the illustration given in Figs. 1 to 4 inclusive, 10 designates a binder base member, and 11 designates a top binder member. The numeral 12 designates posts secured to the base member 10 and extending through a slotted opening in the top binder member 11.

Hingedly connected to the base member 10 is a bottom cover 13, and hingedly connected to the top binder member 11 is a top cover 14. Perforated sheets 15 extend between covers 13 and 14 and have perforations receiving the posts 12. Since the hinged covers 13 and 14 and the perforated sheets 15 are common to such binders and are well known, a further description is unnecessary.

The base binder 10 is formed of sheet metal to provide a hollow interior, as illustrated best in Figs. 3 and 4. The ends of the base are closed by caps 16, held in position by rivets 17. The specific illustration given shows that the top wall 18 of the base member is provided, at an intermediate point, with a slot 19, and a depending flange 20 extends entirely around the slot 19. It will be noted that the depending flange 20 not only extends along the sides of the slot 19 but also across the ends of the slot.

Mounted within the chamber of the base 10 is a slidable block 21 tapped to receive the threaded end 22 of a binder post 12. The block 21 is provided with a channel 23 receiving the depending flanges 20, as shown more clearly in Fig. 4. The flanges 20 thus serve as a guide for the block 21 and also serve to receive the upward thrust of the block 21 when it is drawn upwardly by the rotation of the post 12.

In the operation of the structure shown in Figs. 1, 2 and 4, the posts 12 may be placed in position so as to loosely engage the block 21 and may be moved within the slots 19 to the desired positions for receiving the perforations of the paper sheets 15. If the selected posts 12 are too large for the perforations, smaller posts having, however, threaded extensions 22 of the same diameter, may be substituted. With posts of the desired diameter and located in the desired position for the available sheets 15, the user may now adjust the posts so as to lock them securely in their adjusted position. The locking operation is accomplished simply by rotating the posts 12 so as to cause them to enter more deeply into the threaded openings of blocks 21. This causes the blocks 21 to raise and press against the top portion of the base member 10. The frictional engagement produced by the block 21 against the upper portion of the base member 10 serves to anchor rigidly the post, block and binder just as effectively as if the parts had been originally secured in this permanent relationship.

Should it be necessary, however, to adjust the

posts again to sheets having differently spaced perforations, or to sheets having smaller or larger perforations, the adjustment can be readily accomplished by unscrewing the posts 12. New posts having the desired diameter are then placed in position, as already described, and after the posts have been moved with blocks 21 to their new desired position, the posts may be screwed again into the blocks 21 to provide a new rigid support for posts 12. In the longitudinal movement of the blocks 21, the end portions of flanges 20 serve as stop means for such movement. At the same time, the flanges 20 provide sturdy reinforcement for the metal of the base 10 for the full extent of the slot 19. Since the flanges run longitudinally of the top wall 18 of the base binder, they provide beams which prevent bending of the top wall 19 under the clamping action of the post screw and block..

In the illustration given in Figs. 5 to 7 inclusive, the base member 10^a is provided with a slot 24. Reinforcing the slot 24 is a fixed metal block 25 welded or otherwise secured to the bottom wall of the member 10^a and provided with a transverse slot 26. The transverse slot 26 receives a slidable block 27 threaded to receive the threaded end 28 of the post 12^a. The fixed block 25 is also provided, at its top, with a longitudinal channel 29 through which the reduced threaded end 28 of the post 12^a extends.

In the operation of the structure shown in Figs. 5 to 7 inclusive, fixed block 25 provides the reinforcement for the weakened portion of the binder produced by cutting the slot 24 therein, and such fixed block provides the track for the movable block 27. In other respects, the operation is the same as that heretofore described for the structure in Figs. 1 to 4 inclusive.

In the modification illustrated in Figs. 8 to 10 inclusive, the base member 10^b is provided with aligned slots 30 and 31 in its top and bottom walls respectively. Within the binder base is mounted an elongated slidable block 32. The block 32 is adjustably locked in position by means of two set screws 33 and 34. If desired, a single screw of this type may be employed. The block 32 is provided with an aperture 35 adapted to receive a post 12^b.

Means are provided for supporting the post 12^b, irrespective of its diameter, within the aperture 35 of block 32. Such means comprises a slidable block 36 having a jaw portion 37 adapted to engage the post 12^b, as shown more clearly in Fig. 8. The block 36 is slidably mounted within a recess 38 provided by the block 32, and it is locked in position by a screw member 39 provided with a slotted head 40.

In the operation of the construction shown in Figs. 8 to 10 inclusive, the post 12^b of any desired diameter is placed in position within the opening 35 and the block 32 moved to the selected position. At this point, block 32 is anchored in position by screwing the members 33 and 34 into position, as shown in Fig. 10. At the same time, the post 12^b is firmly anchored within the block 32 by sliding the block 36 into tight engagement with the post and then turning screw 39 to tight locking position.

In the structure shown in Figs. 8 to 10 inclusive, it will be noted that the post 12^b may be of any diameter and that it need not have a threaded end of a selected diameter. The slidable block 36 adjustably engages the post 12^b and binds it securely in position.

In each of the illustrations given, the top binder member 11 may be of any suitable form or construction. In the illustrations given, the binder top member 11 has its ends closed in the same way as the base member 10, and it is provided with longitudinal slots 41 for receiving the binder posts.

With the structures described, it will be noted that the slots in the binder base can be provided at any point longitudinally of the base. For example, if there are three binder posts, one post may be located in the center of the base while the other posts are located near the ends. Since the ends and sides of the base member are intact, the structure is maintained in a sturdy condition while employing relatively thin sheet metal. Further, in the unloosening, adjusting and binding operations required for the structures in Figs. 1 to 7 inclusive, this entire operation can be brought about through simply rotating the posts, and there is no need to modify or change any portion of the binder base walls.

While in the foregoing specification I have set forth certain specific structures in great detail for the purpose of illustrating the invention, it will be understood that such details may be varied widely by those skilled in the art without departing from the spirit of the invention.

I claim:

1. In a post binder having a closed hollow base provided with a longitudinal slot in its upper wall, a plurality of slideably-mounted blocks in said base and accessible through said longitudinal slot, said blocks having threaded openings for receiving the threaded ends of posts, and post members having reduced threaded ends engaging said openings in said blocks and having their shoulders at the reduced end engaging the base about said slot, said blocks being provided with recesses extending thereacross and said base being provided with depending flanges bordering said slot and slideably engaging the walls of said blocks bordering said recesses.

2. In a post binder having a closed hollow base with a longitudinal slot in its upper wall, a plurality of slideably-mounted blocks in said base of lesser width than the width of the base, said blocks having longitudinal recesses in their upper portions and threaded openings extending below said recesses, and posts having reduced threaded ends engaging said threaded openings in said blocks and having shoulders wider than the longitudinal slot of said base and adapted to engage said base on either side of said slot, said base having depending longitudinally-extending flanges along said longitudinal slot providing guides engaging the side walls of said blocks bordering said recesses.

HENRY H. MOORE.
